UNITED STATES PATENT OFFICE.

DAVID C. LAMB, OF ANN ARBOR, MICHIGAN, ASSIGNOR OF ONE-HALF TO ARCHIBALD CAREY, OF DETROIT, MICHIGAN.

SUPPORTING DEVICE.

Application filed June 1, 1925, Serial No. 34,114.

The present invention relates to improvements in supporting devices for box lids, doors and the like.

The invention is particularly adapted for use in connection with the supporting of lids for trunks, cedar chests, radio cabinets, for holding garage doors open, in connection with window casements, as a support for transoms, etc.

10 It is an object of the invention to provide a device of simple yet strong construction which will occupy an inconspicuous position, and will effectively hold the lid, door or other movable member in any adjusted 15 position.

With the foregoing and other objects in view, the invention will be more fully described hereinafter, and will be more particularly pointed out in the claims appended 20 hereto.

In the drawings, wherein like symbols refer to like or corresponding parts throughout the several views:

25 Figure 1 is a vertical section taken through a box with the device applied.

Figure 2 is a similar view showing the lid of the box in the fully open position.

Figure 3 is a vertical section taken on the line 3-3 in Figure 2.

30 Figure 4 is a perspective view of one of the holding members.

Figure 5 is a similar view of the companion holding member.

Figure 6 is a plan view of a modified form 35 of device shown in connection with a garage door indicated in dotted lines.

Figure 7 is a cross section taken on the line 7-7 in Figure 6.

Figure 8 is also a cross section taken on 40 the line 8-8 in Figure 6.

Figure 9 is a bottom plan view of the device with one end portion broken away, and

Figure 10 is a longitudinal section through the device.

45 Referring more particularly to the drawings and for the present to Figures 1 to 5 inclusive 11 designates the body of a box, cedar chest or the like, and 12 the lid or cover thereof hinged in the usual manner as indicated at 13.

Figure 1 shows the closed position of the lid and Figures 2 and 3 the fully open position. The lid is adapted to be held at any angle desired by the improved supporting or holding device composed of the two mem-

bers shown in Figures 4 and 5. The inner member of the holding device consists of a flat relatively thin bar 14 of spring steel or other appropriate material having the perforations 15 near one end for receiving the screw or other fastening 16 by which such end of the bar is hinged to the bracket 17. This bracket is an angle bracket and is secured as by the fastening 18 to the under side of the box lid 12. The bar 14 is split at its opposite end preferably centrally and longitudinally, the separated terminal ends 19 and 20 being bent in relatively opposite directions from the plane of the bar. The bar 14 is also provided with the tongue 21 having its end nearest the terminal ends 19 and 20 connected with the bar. The tongue 21 is produced by making incisions 22 and 23 longitudinally of the bar and to opposite sides and parallel with the median longitudinal line thereof. One end of the tongue is severed completely from the bar, is rounded and bent up from the plane of the bar along the line of flexure or hinge line 24 leaving the flat portion 25 for permitting of resilient movement on the part of the tongue 21.

The bar so formed is adapted to telescope or slide freely in the casing member 26 which is also of spring steel or some other appropriate material. The casing is closed at its bottom, sides and top for the major portion of its length and is formed advantageously, though not necessarily from a single piece of flat steel having its intermediate portion forming the base 27 and its free edges brought together along the central line 28 of the top portion providing the resilient wings 29 and 30 forming such top portion. The sides 31 and 32 are bent upwardly at substantially right angles from the base 27 and the wings 29 and 30 are lapped over toward one another at substantially right angles from the sides 31 and 32, thus providing a casing substantially rectangular in cross section to freely receive the bar 14. At one end the wings 29 and 30 are removed and the base 27 is perforated as indicated at 33 to receive the screw or other fastening 34 by which the casing is pivotally secured to one side of the box body 11. The interior space of the casing is open at both ends and near one end is provided the perforation 35 with the flat sides 36 and the rounded outer end 37.

In the use of the device the bar 14 is slid into the casing and connected to the lid and box as shown and already described. In the act of opening the lid 12, the bar 14 will be drawn out to a greater or less extent from the casing 26 according to the angle at which the lid is opened. In opening the lid to the full position shown in Figure 2, the tongue 21 is brought to a position where it will project through the perforation 35 formed between the two wings of the casing top. Due to its resiliency the tongue will project up at its free end into the perforation and its rounded outer end will strike the outer rounded end 37 of the perforation arresting the further movement of the top and preventing the two members of the supporting or holding device from being separated. The sides 36 of the perforation 35 are flat to agree with the flat sides of the outer tip portion of the tongue 21 and to guide the tongue into and out of the perforation. The tongue will also act against both under edges of the wings 29 and 30 throughout the course of its longitudinal movement in the casing and will thus exert, together with the wings, a resilient tendency which will frictionally resist the movement of the lid and cause pressure to be put thereon. The lid may be held by this frictional resistance in any position of angular adjustment. The tongue 21 acting on the wings 29 and 30 near their free edges 28 will secure a high degree of resiliency and yet sufficient pliability in the movement of the device and the lid. In addition the two separated terminal ends 19 and 20 of the bar 14 will act on the wings 29 and 30. These separated ends will be practically of the same width as the wings 29 and 30 and will exert a tension thereon throughout the breadth of the wings. The terminal end 19 will bear directly upward against the wing 29, while the terminal end 20 will bear downwardly against the base 27 and will force adjacent parts of the bar 14 up against the wing 30 and will serve to keep the tongue 21 close against the two wings.

As shown in Figure 1 the terminal ends 19 and 20 in the fully closed position of the lid 12 will occupy the space just beyond the removed ends of the wings 29 and 30. In fact these terminal ends will snap out from beneath the wings when the lid is fully closed and will be permitted to expand to their fully distended position thereby holding the box lid effectually closed and requiring a considerable application of direct force before the inertia of the device can be overcome. The device forms a very satisfactory, while inexpensive device.

Referring more particularly to Figures 6 to 10 inclusive the bar member 40 in this form of the device is secured by the fastening 41 to the angle clip 42 which is shown

as secured by the fastening 43 to the garage door 44 (dotted lines). The garage door is shown as hinged at 45.

The bar 40 slides back and forth in the casing 46 and is provided at its inner end with the diagonal slots or incisions 47 and 48 which converge rearwardly forming the substantially triangular tongues 49 and 50. These tongues are both bent up into contact with the wings 51 and 52 at the top portion of the casing and they exert a frictional resistance against these wings, the wings being also of resilient material adding to the frictional resistance.

The triangular tongues 49 and 50 are disposed in the path of the perforations 53 and 54 and they are adapted to enter these perforations to arrest the separation of the casing and bar. The casing is provided with the perforation 55 by which it is secured to the top of the garage. The wings 51, 52 are provided with the elongated slot 56 between them and between the perforations 53 and 54 in order to permit the wings to be beaten down at this end upon the bar 40 so that the space between the wings and the bar is much less at this end than between the bar and the remaining portions of the casing. The idea involved is to create a greater frictional resistance at this end of the casing when the tongues 49 and 50 enter the flattened portions of the wings. This occurs when the garage door is nearing the fully open position. Garage doors are heavy and they are apt to be blown shut by the wind and considerable resistance is required to offset this condition. The tongues 49 and 50 in the flattened portions of the wings will develop a very high resistance, suitable for this purpose.

It is obvious that various changes and modifications may be made in the details of construction and design of the above specifically described embodiment of this invention without departing from the spirit thereof, such changes and modifications being restricted only by the scope of the following claims.

What is claimed is:—

1. A holding device of the character described comprising a casing having resilient wings, and a bar slidably fitted in the casing and having resilient portions bent out of the plane of the bar for acting individually against said wings to develop frictional resistance in said wings and in said resilient portions of the bar.

2. A holding device as described comprising a casing having independent resilient wings, a bar slideable in the casing and having resilient end portions bearing frictionally against said wings and a tongue bearing in common against said wings, said casing having a stop to engage said tongue.

3. A holding device as described compris-

ing a casing of resilient material having wings meeting longitudinally thereof, a bar slidable in said casing and having separated terminal ends bent out of the plane of the bar and resiliently pressing against said wings, said bar also having a tongue pressed up from the intermediate portion thereof and bearing in common against said wings,

said wings terminating short at one end whereby said terminal ends of the bar may in the fully telescoped position of the bar extend beyond the wings, said wings having a perforation to receive said tongue in the fully open position of the bar whereby to arrest the movement of the bar. ¹⁰
